STRINGED MUSICAL INSTRUMENT

Filed April 23, 1928

UNITED STATES PATENT OFFICE

JOHN H. LARGE, OF CALDWELL, NEW JERSEY, ASSIGNOR TO INTERNATIONAL MUSICAL CORPORATION, OF HOBOKEN, NEW JERSEY, A CORPORATION OF NEW JERSEY

STRINGED MUSICAL INSTRUMENT

Application filed April 23, 1928. Serial No. 272,076.

This invention relates to a musical instrument having a plurality of strings stretched over a resonator, an object of the invention being to provide means for shifting the supporting point for one end of the vibrating portions of the strings so as not only to change the pitch of the strings, but also to produce a marked change in the timbre of the notes given out by the strings when vibrated. This object of the invention is attained by alternatively supporting one end of the strings either on a bridge located on a solid portion of the body of the instrument, or on a supplementary bridge mounted on the cover portion of the resonator which forms a part of the body of the instrument. In the latter case, the vibrations of the strings are transmitted mechanically to the vibratile cover portion on which the supplementary bridge is mounted, so that a louder and relatively harsher tone is thus produced. An instrument embodying the invention may thus be made to resemble in tone quality either a harp or a banjo, according to the location of one of the end supports for the wires.

Another object of the invention is to provide improved means for damping and keeping silent certain of the strings to produce chords by vibration of the other strings, when a pick or equivalent playing instrument is drawn across all the strings. For this purpose, simplified dampers or muffler bars are provided, these bars being so hung as to engage the strings with evenly balanced pressure throughout the length of the bar, this being accomplished by relatively simple structure.

For a more complete understanding of the invention, reference is had to the following description of an embodiment thereof illustrated on the drawing, of which—

Figure 1 is a plan view of an instrument embodying the invention.

Figure 2 is a longitudinal section on the line 2—2 of Figure 1.

Figure 3 is a transverse section on the line 3—3 of Figure 1.

Figures 4 and 5 are fragmentary longitudinal sections showing modified forms of a part 50 of the invention.

Figure 6 is a fragmentary cross section similar to Figure 3, showing a modified form of structure for the muffler manuals.

Referring to the drawing in detail, 10 represents the body of a musical instrument from which extends a neck 11 which is integral therewith. The body and neck together may, as shown on the drawing, comprise a hollow resonator having a bottom plate 12, side walls 13 extending around the periphery of the body and neck, and a top member 14. The latter may be apertured as at 15 for resonance. The side walls 13 are preferably sufficiently substantial to provide necessary stiffness for the instrument as a whole. The portion 16 of the side wall 13 which is at the end of the body portion remote from the neck, may be made of extra width as shown in Figure 1 to provide a direct support for a bridge 17 over which the strings 18 pass before being secured as at 19 to the body of the instrument. The other ends of the strings 18 may be secured as at 20 at points adjacent to the free end of the neck 11. The strings having a higher pitch must as usual be successively shorter than those having lower pitch. In order however, to avoid the necessity of extending the fastening elements 20 too far down the side of the neck 11, the strings may be successively shortened to some extent at their other end by inclining the bridge 17 to the axis of the instrument. This arrangement affords room for a set of muffler manuals for use in playing the chords on the instrument extending across the neck of the instrument without unduly lengthening the neck. According to the invention, a supplementary bridge 21 is provided, this bridge being arranged parallel to the bridge 17 and spaced therefrom. The bridge 21 is mounted on a portion of the top member 14 of the body which is not directly underlaid by any portion of the side walls 13. The bridge 21 is provided with a removable spring-engaging member 22 which as shown may comprise

a metal rod adapted to rest in a suitable longitudinal groove in the upper surface of the base member of the bridge 21, these elements being so arranged that the rod 22 when in place supports the strings 18, but when re- 100

5 moved leaves the strings supported at their lower end solely by the bridge 17. The auxiliary bridge 21 not only changes the pitch of all the strings, but also produces a marked change in the tone quality of the strings.
 10 When the lower ends of the strings are supported only on the bridge 17 which is directly underlaid by the portion 16 of the side walls 13, the strings 18 give forth a relatively quiet tone similar in quality to those of a harp. When, however, the strings are supported by the bridge 21 which is not underlaid by any portion of the side wall 13, the vibrations of the strings are directly and mechanically imparted to the vibratory top member 14 of the resonator so that the strings when played give forth a distinctly louder and somewhat harsher tone. Thus by the insertion of the rod 22, the instrument may virtually be changed from a harp or guitar to the equivalent of a banjo or the like. The supplementary bridge 21 may be constructed in a variety of ways besides the particular one shown in Figure 1. For example, as shown in Figure 4, the bridge may comprise a bar 23 pivotally supported at its ends and provided with a metal piece 24 extending along an edge thereof. This bar may be swung from its operative position as shown 20 by full lines in Figure 4 to an inoperative position indicated in dotted lines. When the bar is in operative position, the lower edge thereof rests directly on the top member 14 of the instrument. Another modified form 25 is illustrated in Figure 5, this form being a bar similar to the one shown in Figure 4, but pivoted on its mid axis rather than on an axis nearer to the surface of the member 14. This bar is rockable between its operative 30 position as shown in full lines wherein the upper edge supports the strings 18 and the lower end rests directly on the top member 14, and its inoperative position wherein it is out of contact with both the strings and 35 top member.

In order to facilitate the playing of chords on the instrument, a set of muffler manuals may be provided, these bars being supported from one side of the neck to the other side 40 thereof and being manually operable to damp certain of the strings and keep them silent. When all the strings are plucked, the strings which are not damped being thus sounded to make a desired chord. The muffler manuals 45 herein disclosed are of improved and simplified construction. Each manual may comprise a rigid member 25 which may conveniently be in the form of an inverted metal channel member. In the embodiment illustrated in Figure 3, this member is rockably supported as at 26 at one end thereof. A bar 27 is loosely fitted within the channel and is supported at substantially its mid point 28 to rock within the channel. In order to permit a slight rocking motion of the bar 27

within the channel 25, the bar 27 is tapered from approximately its mid point toward one end, the lower edge of the bar being straight. On this straight lower edge are mounted a plurality of suitable damper pads 29 which may be of felt or other suitable material and which are adapted to rest against certain of the strings 18 when the manual is depressed to operative position. In order to hold the manual resiliently in its elevated inoperative position, suitable spring means may be provided. To this end, each manual may be provided with a leaf spring 30, one end of which may be secured as at 31 to a side wall 32 of the housing which contains the manuals. The free end of the spring 30 may be passed about the pivot member 26 and may rest against the under face of the channel member 25, thus pressing the channel member upwardly. A stop block 36 is provided above the right hand end of the bar 27 (as viewed in Figure 3), against which the end of the bar engages when it is raised by the spring 30 acting through the channel member 25 and the pivot pin 28. This stop block prevents the right hand end of the bar from rising too far when the bar itself rises, and thus holds the bar in a horizontal position when it is elevated. The housing for the manuals may comprise a pair of end walls 32 mounted on the sides of the neck 11 of the instrument, and a cover tablet 33 supported on the walls 32 and extending over the strings from one side of the neck to the other. This tablet covers all the manuals and protects them from injury and from dust. In order to enable the operator to depress the manuals to operative position, each manual may be provided with a suitable plunger 34 having a finger piece 35 which may be pushed. The lower end of the plunger 34 rests on the upper face of the channel member 25. Suitable indicia to indicate the nature of the chord which is sounded when any one of the damper bars is depressed, may be placed either on the top of the finger piece 35 or on the face of the tablet 33 at a point adjacent to the plunger 34. In order to simplify construction, the pivot member 26 may, as shown in Figure 2, comprise a single rod extending through all the channel members 25 and being in turn supported at its ends by one of the end walls 32 of the manual housing.

A modified form of action is illustrated in Figure 6. In this form, a pair of strips 37 are shown in place of the cover 33 illustrated in the other form. These strips are mounted respectively on the two side walls 32, and their inward edges project over the edges of the walls. The channel members 25 are of sufficient length to extend under the strips 37 at both ends and to engage the under faces thereof when in elevated position. There is no mechanical connection between the channel member 25 and the housing, nor

between the channel member 25 and the bar 27. The latter is pressed upwardly against the channel member by any convenient means such as a pair of compression springs 38 bearing against the under face of the end portions of the bar 27. The bar 27 in turn presses the channel member 25 upwardly against the two strips 37. A suitable finger piece 39 may be mounted on the channel member 25 at any convenient point. When the finger piece 39 is pressed, the left hand strip 37 acts as a fulcrum for the channel 25 and the latter bears on the bar 27 at or near its mid point, forcing the latter down against the springs 38. These springs raise the bar and channel member when the finger piece is released. This embodiment of the invention provides an exceedingly simple but reliable action. The use of strips 37 in place of a complete cover 33 is not restricted to the form of the invention shown in Figure 6, but is equally possible in the form shown in Figure 3 in which case a fixed finger piece 39 would replace the separate finger piece 35.

Having thus described certain embodiments of this invention, it should be evident to those skilled in the art that various changes and modifications might be made therein without departing from its spirit or scope as defined by the appended claims.

I claim:

1. A musical instrument having strings, a body comprising side walls and a vibratile top member supported thereon, means mounted on said top member directly over a portion of said side walls for supporting one end of the vibratory portion of the strings, and supplementary means for supporting said strings at points spaced from the first mentioned support means, said supplementary means being mounted on a vibratile portion of said top member and including means for engaging and disengaging said supplementary means and said strings.

2. A musical instrument having strings, a body comprising side walls and a top member thereon, a bridge for said strings mounted directly over a portion of said side walls, a supplementary bridge mounted on a portion of said top member not supported from beneath, and means for bringing said supplementary bridge into and out of supporting engagement with said strings.

3. A stringed musical instrument having a body comprising side walls and a top member supported thereon, a bridge mounted on a portion of said top member directly underlaid by said side walls, and an auxiliary bridge comprising a base member mounted on a portion of said top member not directly supported from beneath and a removable string-engaging piece between said base and the strings.

4. A musical instrument having strings, a hollow resonating body comprising side

walls and a top member supported thereon, a string-supporting bridge mounted on a portion of said top member directly underlaid by said side walls, and a supplementary bridge parallel to and spaced from the first mentioned bridge, said supplementary bridge having a base mounted on a portion of said top member not supported from beneath, and a removable string-engaging member between said base and the strings.

5. A musical instrument having a hollow body with a side wall and a top member on said wall, a hollow neck extending from and integral with said body, a plurality of strings extending from points adjacent to the free end of the neck to points adjacent to the further end of the body, a string-supporting bridge mounted on a portion of said top member adjacent to said further end of the body and underlaid by a portion of said side wall, said bridge being inclined to the axis of the instrument, and a supplementary bridge parallel to the first mentioned bridge and supported on a portion of the top member not supported from beneath, said supplementary bridge having a portion movable to leave the strings unsupported thereby.

In testimony whereof, I have affixed my signature.

JOHN H. LARGE.
